PORTABLE STAMP MILL

Magnus Palmason, Sault Ste. Marie, Ontario,
CanadaApplication October 23, 1934, Serial No. 749,662
In Canada October 31, 1933

4 Claims.

(Cl. 83—57)

This invention relates to high speed portable stamp mills and it consists in the constructions, arrangements and combinations herein described and claimed.

5 The invention has for an object the provision of a stamp mill for reducing ore, which is inexpensive of construction and light in weight, so as to make it readily portable from place to place to meet the requirements of the average prospector.

10 It is a further object of the invention to provide a stamp-mill in which a pair of crushing hammers are actuated through a single drive means.

15 It is another object of the invention to provide a novel adjusting means between the walking beam and its fulcrum, to accommodate for wear between the hammers and anvil.

20 It is a further object of the invention to provide a clutch means for retaining the crushing hammers in neutral position until a proper working speed has been attained by the driving engine.

25 It is a still further object of the invention to provide a novel lubricating system for the connecting rods of the mill.

30 Additional objects, advantages and features of invention will be apparent from the following description, considered in conjunction with the accompanying drawings, wherein

35 Figure 1 is a side elevation of a mill constructed according to my invention.

Figure 2 is a front elevation thereof with a portion broken away.

Figure 3 is a rear elevation of the mill.

35 Figure 4 is an enlarged view, partly in section, illustrating the drive mechanism and clutching means.

Figure 5 is a detail of the clutch mechanism, 40 parts of the frame structure of the mill having been removed.

Figure 6 is an enlarged detail view of the connection between the walking beam and fulcrum.

Figure 7 is a side elevation, partly in section, of 45 the lubricator.

Figure 8 is a cross section thereof on the line 8—8 of Figure 7.

There is illustrated a frame 10, preferably 50 formed of angle iron, comprising a base plate 11, medially of which there is a sub-frame 12 which functions as a fulcrum for the crushing hammers, as will be presently described. At the forward end of the frame 10, a pair of uprights 13 are secured, as at 14, the upper ends of the 55 uprights being connected by a cross beam 15 and

intermediate the length of the uprights 13, a cross beam 16 is secured. The framing defined by the uprights 13, and the cross beams 15 and 16 provide for the mounting of the crushing hammers, and since the frame will be subjected to considerable strain due to impact of the hammers, the framing is preferably braced, as at 17. The braces 17 are shown as secured to the upper ends of the uprights 13 and extend to the rear of the base 10, where they are secured in any approved manner, as by bolts or otherwise. The braces 17 may be connected by a cross beam 18, if desired.

Upon the base 10, there are a pair of anvils 19, positioned in a side by side relation, and enclosing these anvils there is a housing 20 for containing the ore to be crushed, and in order to readily determine the degree of fineness of the ore, the front wall 21 of the housing has a screened opening 22.

20 The cross beam 15 is provided with a pair of vertically disposed apertures and the cross beam 16 is similarly apertured, these latter apertures being in alignment with those of the cross beam 15 and reciprocably mounted within each pair of aligned apertures there is a rod 23. The rods 23 are shown as comprising a pair of sections 23a and 23b connected by a spool-shaped head 24. One end of the sections 23b of the rods are disposed within the housing 20 and mount crushing 30 hammers 25. It will be understood that the hammers are disposed immediately above respective anvils 19 and cooperate therewith during crushing of ore.

In order to actuate the hammers 25 walking 35 beams 26 are rockably mounted, as at 27, upon the upper portion of the sub-frame 12. The pivots for the walking beams is clearly shown in Figure 6, wherein a yoke 28 mounts the walking beam by the pin 27. The yoke 28 includes a 40 threaded stud 29 extended through a cross beam 12' of the frame, and upon the stud 29 there are lock nuts 30—31 arranged in opposed relation to the beam 12'. By the construction, it will be apparent that the pivot 27 of the yoke may be 45 raised or lowered by merely loosening the nuts 30—31 the desired degree, and then tightening the nuts. This adjustment will be required after long continued use of the mill, since there will obviously be wear between the anvils and hammers.

50 The forward ends 32 of the walking beams terminate in disk-shaped heads 33 of a size to be freely received between the heads 34 of respective spools 24, and in order to insure a se- 55

cure contact between the spools and heads 33 and otherwise tension the beam 26, a tension spring 35 is fixed between the beam and the housing 20.

5 It should be noted that during operation of the mill, by the construction of the disk heads 33 acting upon the heads 34 of the spools, a slight rotary action will be imparted to the rods 23, which will prevent uneven wear upon the 10 rods and guide apertures.

Upon the rear portion of the base 10 there is mounted a pair of bearing members 36, within which there is journaled a shaft 37. Outwardly of each of the bearings 36, and keyed to the 15 shaft 37 there are combined fly and gear wheels 38. The gears are indicated at 39 and are formed upon the periphery of the fly-wheels, these gears 39 being in mesh with respective gears 40 keyed to a shaft 41. The shaft 40 is suitably mounted 20 in spaced bearings 42, and between the bearings 42 a drive pulley 43 is keyed to the shaft 41, the pulley being driven from any suitable source through a belt 44.

Attention is now invited, particularly, to Figures 4 and 5 of the drawings for an understanding of the clutch mechanism and the drive for the walking beams.

The fly-wheels 38 are identical in construction and therefore a description of one will suffice for 30 a clear understanding thereof. A slot 45 is formed in the fly-wheel extending diametrically thereof, terminating in opposed bays 46, adapted to receive a wrist pin 47 of a connecting rod 48. The other end of the connecting rod 48 is pivotally connected to the walking beam 26, as at 49. By this construction, as the slot 45 assumes a vertical position and the connecting rod 48 is in its elevated position, the uppermost bay 46 receives the pin 47 and thus the connecting rod pulls the 40 walking beam downwardly so as to raise its associated rod 23 to raise the hammer 25 associated therewith. Upon reaching the opposite dead center of the fly-wheel the pin releases itself from the bay and allows the pin to pass upwardly through the slot where it is engaged by the other bay which similarly operates to again raise the hammer.

It will be readily seen that by the construction presented, the rotation of the fly-wheels operates 50 to raise the hammers successively, in order that it may deliver working strokes against the anvils 19 so as to reduce the ore contained in the housing 20. The walking beam is so adjusted that the force of the blow is not imparted to the wrist pin 47.

A clutch mechanism, generally indicated at 50, is provided, being utilized to maintain the hammers in a neutral position, until the engine or other power unit has attained sufficient speed. 60 The clutch comprises an arm 51 having a hook end 52 adapted to fit over and engage the head 53 of the wrist pin 47 when it is in mid position. In this position of the pin no force can be transmitted to it by the slotted wheel. The arm 51 is 65 integral with a bar 54 disposed horizontally in bearings 55. The bar 54 is shiftably mounted in the bearings 55 so as to permit the arm 51 to shift to and away from the head 53. Coiled about the bar 54 is a tension spring 56 for forcing the 70 arm away from the head 53 and on the outside of one of the bearings 55 is a shoulder 57 that limits the movement of the bar. The bearings 55 are vertically adjustable in 75 order to enable the hooked end 52 of the arm to

be set at the correct position for engaging and retaining the head. The adjustment of the bearings may be accomplished in various ways, but that shown in the drawings, by way of illustration, consists of threaded shanks 58 having lock nuts 59 engaged thereon by adjustment of which the bearings can be raised or lowered, as desired.

In use of the clutch members, the hooked end 52 is forced over the head 53 against the pressure of the spring 56 and the flywheel 38 is turned so 10 that the slot 45 assumes a vertical position. Such movement of the wheel 38 will bring the head 53 in position to be engaged by the hooked end 52. The frictional contact between the head and hook is sufficient to maintain the parts in neutral position.

When the engine has attained its full working speed, the walking beams are manually depressed in order to lower the connecting rods 48 and thus free the heads 53 from the hooked ends of the arm 20 of the clutch. This permits the spring 56 to shift the arm away from the head 53. The connecting rods can only be depressed when the slots in the wheels are in vertical position and when once disengagement takes place the force of the hammers causes them to rise and come into operation.

In Figures 7 and 8, I have illustrated a means for supplying lubricant to the wrist pin and slot. A container 60 is secured to each of the connecting rods 48, a conduit 61 leading therefrom to a point of discharge 62. The discharge 62 it will be noted opens directly within the slots 45 and upon the wrist pins 47. In order that a predetermined quantity of lubricant will be ejected at the slot, the container 60 includes a ball valve 35 cage 63, housing a ball valve 64. The ball valve rests within a seat 65 communicating with the conduit 61, and in order to maintain the ball seated, the valve comprises a stem 66 and cross pin 67 and upon the stem there is a helical spring 40 68. The spring 68 engages the pin 67 and an adjustable cap 69, and there will thus be a downward pressure upon the valve. However, the ball 64 is unseatable, upon impact, such as will be transmitted upon completion of each stroke of 45 connecting rods, and when so unseated will permit a discharge of lubricant into the conduit 61. Thus the lubricant will be automatically fed to the slot and wrist pin.

I claim:—

1. In a stamp mill, a frame, a walking beam pivotally supported thereby, means for tensioning the beam, a connecting rod on the beam, a rotary disk carried by the frame, said disk having a diametrical slot, a pin on the connecting rod engaged in the slot, means for rotating the disk, and a hooked lever supported by the frame and movable into engagement with the pin to frictionally hold the pin in a position concentric with the axis of rotation of the disk.

2. In a stamp mill, a frame, a walking beam pivotally supported thereby, means for tensioning the beam, a connecting rod on the beam, a rotary disk carried by the frame, said disk having a diametrical slot, a pin on the connecting rod engaged in the slot, means for rotating the disk, bearing members carried by the frame, a bar reciprocably mounted therein, a hook member rigidly connected with the bar and adapted to frictionally engage the pin for holding the same in a neutral position in the slot, and spring means for urging the bar to a position to release the hook member from the pin.

3. The structure of claim 2 in which the bear-

ings are adjustable to set the hook member at a position for holding the pin concentric with the axis of the disk.

4. In a stamp mill, a frame, a walking beam rockably supported thereby, a spring member connected between one end of the beam and a portion of the frame tending to draw the beam downwardly, a connecting rod on the other end of the beam, a rotary disk on the frame, said disk having 10 a diametrical slot, a pin on the connecting rod

engaged in the slot, means for rotating the disk, bearing members carried by the frame, a bar reciprocably mounted therein, a rigid hook member on the bar adapted to frictionally engage the pin for holding the same in a neutral position in the slot, and spring means for urging the bar to a position to release the hook member from engagement with the pin. 5

MAGNUS PALMASON. 10
